J. M. ROHLFING,
CAR END FRAMING CONSTRUCTION,
APPLICATION FILED DEC. 4, 1915.

1,209,036.

Patented Dec. 19, 1916.

UNITED STATES PATENT OFFICE.

JOHN M. ROHLFING, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

CAR-END-FRAMING CONSTRUCTION.

1,209,036.

Specification of Letters Patent. Patented Dec. 19, 1916.

Application filed December 4, 1915. Serial No. 65,029.

To all whom it may concern:

Be it known that I, JOHN M. ROHLFING, a citizen of the United States, residing at the city of St. Louis, State of Missouri, have 5 invented a certain new and useful Improvement in Car-End-Framing Construction, of which the following is a full, clear, and exact description, such as will enable others skilled in the art to which it appertains to 10 make and use the same, reference being had to the accompanying drawings, forming part of this specification.

This invention relates to certain improvements in end structures for railway cars, 15 and consists in a new and improved arrangement of framing parts at the end of the car so arranged as to provide vertical posts or framing members designed to resist cargo thrusts against the end, and connected in a novel and effective manner to 20 the end sill and upper framing members in such fashion as to secure great strength.

My invention in some respects constitutes an improvement on the construction illustrated in U. S. Letters Patent to Henrion and McRobbie granted October 24, 1905, No. 802,689, the particular improvements there-over residing in the improved connection of 25 the framing members and the increased stability in the structure thereby secured.

The principal object of my invention is to provide an end framing construction in which commercial metallic forms are employed in conjunction with car framing 35 members which are commonly of wood, the construction being designed for application either to new cars, or for substitution in old cars, and certain of the metallic members being designed to supplant certain wood 40 framing members commonly employed in the car framing.

Other and further objects of the invention will be obvious or pointed out hereinafter.

In the drawings—Figure 1 represents a 45 partial end view of a box car in which my invention is embodied; Fig. 2 represents a partial longitudinal vertical section, the same being taken substantially on line 2—2 of Fig. 1; Fig. 3 is a detail showing a top 50 view of the corner construction; Fig. 4 is a cross sectional detail, the same being taken substantially on line 4—4 of Fig. 1; Fig. 5 is another cross sectional detail, the same being taken substantially on line 5—5 of Fig. 55 1; Fig. 6 is a sectional detail taken substantially on line 6—6 of Fig. 2.

Referring to the illustrations in detail, it will be understood that the box car shown is of common construction, and includes a plurality of longitudinal sills 1, an end sill 2, side plate 4, end plate 5, ridge pole 6, corner posts 9, fascia plate 10, and flooring 11, all constructed in usual fashion and disposed in a customary relationship. In conjunction with these, I employ a sill plate 7 60 which may be of general Z or L section so that it will conform to the outer corner of the end sill extending down on the face thereof behind the dead block 8 and to receive the truss rods 12, and extending back 65 over the upper face of the end sill to the line of the wall sheathing, where it terminates in an upwardly directed flange. This sill plate is secured to the end sill by horizontal bolts 14 and vertical bolts 15. 75

In connection with the end plate 5, I employ a marginal angle member 16, preferably of Z cross section, the same being applied to the lower edge of the end plate with a flange extending up behind the inner face 80 of the latter and secured thereto by bolts 17, and the outer flange extending downwardly adjacent the outer corner of the end plate. At its ends the marginal angle member is secured to the corner posts 9 by angular extensions 18. The marginal member 16 is also securely anchored at its ends to the side plates, the means for effecting such connection comprising a connecting angle 22 which is bolted to the side plate, and a 90 gusset member 23 riveted to the horizontal flange of the connecting angle and the web of the marginal member 16. The sill plate 7 is secured to the corner posts in somewhat similar fashion by the socket castings 19 95 which are riveted to the horizontal flange of the sill plate, and bolted to the corner posts.

By virtue of the structure just described, it will be observed that I provide auxiliary transverse framing members securely combined and co-operating with the end sill and end plate providing metallic surfacings for outer faces thereof and affording means of connection between said members and the corner posts. 100 105

Spaced apart at suitable intervals transversely of the end, I dispose vertical angle members 20, the same being preferably of Z section in order to secure greatest strength in combination with convenience in assembling. At their upper ends these vertical members abut the horizontal web of the 110

marginal member 16, and fit behind the depending outer flange thereof. At their lower ends the vertical members abut the horizontal flange of the sill plate 7 and the 5 upstanding vertical flange thereof. Three-sided corner angles 21 secure the vertical members to the marginal member 16, said corner angles being riveted to the webs and flanges of the vertical members and to the 10 web of the terminal member. Similar corner angles connect the vertical members at their lower ends to the sill plate 7, said angles being riveted to the webs and flanges of the vertical members and to the 15 horizontal web of the sill plate. This disposal of the vertical members brings their inner flanges into alinement, and to these flanges are applied the sheathing boards 24 which form the end wall of the car, said boards 20 being secured in the usual fashion at their ends to the corner posts, and by bolts 24^a. In an end framing of this form, it will be observed that the vertical members 20 co-operate with the end sill and end plate to 25 form vertical supporting members or posts at the end of the car, which posts function to support the load of the roof and upper framing. In conjunction with the marginal member 16 and sill plate 7, these vertical 30 members form a stable end frame securely anchored to the underframe by the truss rods 12, and to the side plates by the gusset 23 and joint angle 22. At its corners, this framing securely ties the corner posts by 35 virtue of the socket castings 19 and terminal extensions 18.

In assembling this structure or in applying it to a car from which the end wall has been removed, the sill plate 7, marginal 40 plates 16, vertical members 20 and attaching members 19, 18, 23 and 22, all being riveted together, are disposed in place at the end of the car as a unitary structure, and then the securing bolts 14, 17 and 22^a 45 are secured in place, after which the end wall sheathing is applied. As a result of this construction, it will be observed that the end wall is greatly strengthened by the rigid vertical members 20 to resist cargo 50 thrusts and that said vertical members 20 are in turn securely anchored to the upper and lower framing members of the car, not only the end sill and end plate, but also the longitudinal framing members; the 55 framing members themselves, such as the side plates, end plates and corner posts, the corner posts and underframe, and the underframe and end plates are secured in very substantial and effective manner. Moreover, 60 certain features of the construction perform specifically important functions, the marginal member 16 and the sill plates 7 operating to prevent shattering of the end plate and center sill by strains in the vertical 65 members 20, and the contour of the termi-

nal member and sill plate operating effectively to prevent ingress of water at top and bottom of the wall structure. The vertical members 20 also provide convenient attaching places for ladders or grab irons. 70 In connection with them it may be desirable to employ an angle member 25 attached to the corner post to which one end of the ladder rod or grab iron is riveted, the other end thereof being secured to the outer flange 75 of the adjacent vertical member 20. The form of the members, of course, enables my using the same form of corner angle 21 in all places where a connection between the vertical and horizontal members is desired. 80

I am aware that the construction herein illustrated and described is capable of modifications and adaptations not specifically indicated, without departing from the spirit and scope of the invention indicated in the 85 following claims.

What I claim is:

1. An end framing for railway cars comprising the combination of end sill, end plate, side plates and corner posts, an angular sill plate applied to the end sill on its top and outer sides, a marginal metallic member applied to the lower margin of the end plate, vertical members extending between and secured to said sill plate and said marginal member, wall sheathing abutting said vertical members, members at the extremities of the sill plates engaging the corner posts, and members at the extremities of the marginal member secured to the 100 corner posts and the side plates.

2. A car end framing construction comprising the combination with wooden end sill, end plate and side plates, of vertically disposed metallic members, transversely extending metallic members interposed respectively between the lower extremities of said vertical members and the end sill and the upper extremities of said vertical members and the end plate, attaching means 105 securing said transversely extending members respectively to the end sill and the end plate and both of said transversely extending members to the vertically disposed members, and means disposed at the extremities 110 of said transversely extending members for securing them to longitudinal framing members of the car.

3. A car end framing construction comprising vertically disposed bar members, transversely directed metallic members connecting said vertical members at their ends, said transversely extending members being shaped to conform to the car end sill and end plate respectively, and means for securing said 125 transversely extending members to side framing members of the car.

4. An auxiliary end framing for cars comprising transverse metallic members adapted to be fitted to the end sill and end plate, 130

- vertically disposed bar members extending intermediate said transverse members and secured thereto, and means at the extremities of said transverse members for engaging corner framing members of the car.
5. An end framing for cars comprising an end plate, a Z bar having its web applied to the lower face of the end plate and one of its flanges abutting the inner face of the end plate, an end sill, an angular sill plate having one flange overlying the end sill and another flange abutting the outer face of the end sill, bar members extending intermediate the said Z bar and sill plate and secured at their extremities thereto, end wall planking supported against said bar members, and means for securing the Z bar and the sill plate to the end plate and end sill respectively.
- 10 6. A car end framing comprising an end plate, a transverse bar member applied to the lower face thereof, an end sill, a transverse bar member applied to the upper face thereof, vertically arranged bar members disposed intermediate the end plate and end sill and secured at their ends to said transverse members, and means for securing the transverse members to the end plate and end sill respectively.
- 15 7. A car end framing including an end plate, corner posts supporting the end plate, an end sill supporting the corner posts, a transverse bar member applied to the lower margin of the end plate, a transverse bar member applied to the upper surface of the end sill, vertical bar members disposed intermediate the end sill and end plate and secured to said transverse bar members, and terminal members at the extremities of said transverse bar members engaging the corner posts.
- 20 8. An end structure for railway cars including an end plate, a transverse bar member applied to the lower surface thereof, an end sill, a transverse bar member applied to the upper surface thereof, Z bars extending intermediate said transverse members, and three-sided gusset members connecting the webs and flanges of said Z bars with the respective transverse bar members.
- 25 9. An end framing for cars including an end plate, corner posts supporting the end plate, an end sill supporting the corner posts, transverse bar members affixed to the end plate and end sill respectively and terminating adjacent the corner posts, vertical bar members connecting said transverse bar members intermediate the corner posts, and means connecting the extremities of the transverse bar members with longitudinal car framing members.
- 30 10. In a car end framing construction, an end sill, a transverse bar member supported thereon, vertical bar members supported on said transverse bar member, a marginal bar member supported on said vertical bar members, an end plate supported on said marginal member, side plates, and means connecting said marginal member at its extremities with the side plates.
- 35 11. In a car end framing construction including an end sill and end plate, vertical bar members, end wall planking supported by the vertical bar members, and transverse bar members connecting the ends of the vertical bar members and securing the vertical bar members to the end sill and end plate.
- 40 12. An end framing for cars comprising transverse bar members shaped for attachment directly to the end sill and end plate, vertical bar members extending intermediate said transverse bar members and adapted for the application of wall planking, and terminal securing members disposed at the extremities of the transverse members, all for the purpose described.
- 45 13. In an end framing for railway cars, the combination of an end sill, corner posts, a transverse bar member secured to the end sill and terminating adjacent the corner posts, and terminal members affixed to the transverse member and embracing portions of the corner posts adjacent their lower extremities.
- 50 14. In a car end framing construction, an end sill, an end plate, a Z bar having its web applied to the lower margin of the end plate and one of its flanges bolted against the inner face of the end plate, its other flange depending on the exterior of the car wall, vertical bar members secured to said Z bar behind the depending flange thereof, and means for securing said vertical bar members at their lower extremities to the end sill.
- 55 15. A car end frame construction including an end sill, an end plate, transverse bar members applied to the facing surfaces of the end sill and end plate, vertical bar members having their extremities abutting said transverse bar members and secured thereto, and end wall planking abutting against said vertical bars.
- In testimony whereof I hereunto affix my signature in the presence of two witnesses, this 19th day of November, 1915.
